(Cl. D81—4)

FIG. 1

Fig. 4

Fig. 1 is a front elevational view of a range embodying my new design;

Fig. 2 is a side elevational view thereof;

Fig. 3 is a left front isometric view of such range with the lower sliding portion thereof in closed condition; and

Fig. 4 is a view similar to Fig. 3 but showing the lower sliding portion in its forwardly extended condition.

The essential features of my design reside in the portions shown in full lines.

I claim:

The ornamental design for a range, as shown and described.
